PLASTIC FAUCET HANDLE

Harper Landell, Whitemarsh, Pa., and Thomas C. Abrahamsen, Haddonfield, N.J., assignors to Speakman Company

Filed Mar. 3, 1966, Ser. No. 1,264

Term of patent 14 years

(Cl. D91—3)

FIG. 1.

FIG. 2.

FIG. 3.

FIG. 4.

FIG. 5.

FIGURE 1 is a top plan view of a plastic faucet handle or the like embodying our new design.

FIGURE 2 is a side elevational view of the plastic faucet handle, as shown in FIGURE 1.

FIGURE 3 is a side elevational view, similar to FIGURE 2, showing the lever portion behind the handle.

FIGURE 4 is similar to FIGURE 3, showing the lever portion in front of the handle.

FIGURE 5 is a bottom plan view of the plastic faucet handle.

The characteristic features of our design reside in the vertical striations on the interior of the lower portion of the faucet handle.

We claim:

The ornamental design for a plastic faucet handle, as shown and described.
